SHOWER CURTAIN RING

Filed July 31, 1926

UNITED STATES PATENT OFFICE

LOUIS AUSTER AND MARIE AUSTER, OF NEW YORK, N. Y.

SHOWER-CURTAIN RING

Application filed July 31, 1926. Serial No. 126,175.

This invention relates to rings for supporting and sliding curtains for enclosing bath tubs to prevent the discharge of water on the floor of a bath room when a person takes a shower bath. It has been proposed to provide rings having an upper portion which is shaped to conform to a supporting rod which receives the rings whereby the curtain may be moved to an operative or inoperative position. Such type of ring, however, does not permit a ready sliding movement of the curtain because of the fact that the rings become jammed and tend to move into each other so that it necessitates particular care in arranging the curtain in its proper position. Furthermore the frictional contact between the metal of the rings and the supporting rod tends to prevent easy movement of the rings on the rod so that while certain of the rings will readily move forward other rings will resist the movement and thus require additional effort for placing the curtain either in an operative or inoperative position.

The present invention is intended to eliminate these objections so that when an edge of the curtain is grasped and the same is moved to an operative or inoperative position the rings will slide along the supporting rod freely and readily since rollers are provided to eliminate the frictional contact between the rings and the rod.

A further object of the invention is the provision of a ring which may be readily applied to the curtain and likewise to the rod which will not only move freely over the rod but which will tend to maintain the rings in a predetermined plane for maintaining the folds of the curtain at predetermined intervals and to permit ready positioning of the curtain.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient features of the in-

vention as expressed in the appended claims. In the drawings:

Figure 1 is a view in perspective of a shower curtain for bath tubs.

Figure 2 is a view in elevation with a part in section showing one form of the ring.

Figure 3 is a view in elevation with a part in section of another form of the ring.

Figure 4 is a horizontal section taken along the line 4—4 of Figure 3.

Referring more particularly to Figure 1, an application of my invention is shown in supporting position for a curtain 10 which is carried by a pole 11 by means of rings 12. The pole, as is usual, is supported at its opposite ends by means of bosses 13 mounted on plates 14. These plates are secured to the wall of the bath room in any approved manner. The pole has a straight portion 15 running longitudinally above the bath tub (not shown) and an offset end portion 16 which is adapted to support the curtain 10 in an inoperative position.

The usual shower fixture 17 is secured to the wall 18 of the bath room and has an arm 19 extending outwardly upon the end of which is provided a perforated nozzle 20 disposed directly over the tub in such a manner that the water will be sprayed directly to the user of the tub.

Referring more particularly to Figure 2 it will be seen that a ring is provided in which a pair of arms 36 are pivotally connected together at 37. These arms are extended upwardly then outwardly at 38 and then curved as shown at 39 to provide a sufficient space to receive the rod 11. The upper free ends of the arms 39 are bent inwardly as shown at 40 and are brought adjacent each other as shown at 50 when said straight portions are received by the central longitudinal passage in the roller 41. The roller 41 has an annular groove 29 which will ride on the pole 15.

In applying the ring shown in Figure 2 it is only necessary to withdraw one of the straight portions 40 of either of the arms 39 from the roller or pulley 41. This free arm then is inserted through an eye 28 of the curtain 10 and the arms are brought together with the straight portion 40 being inserted

within the longitudinal axial passage of the pulley 41 after said arms have been placed in embracing relation with the rod 11 so that the pulley 41 may rest in normal position on the rod 11.

10 The straight portions 40 of either of the arms 39 are made of such a length that they may be inserted easily within the longitudinal axial passage of the pulley 41, but will be retained against displacement from the pulley.

Referring more particularly to Figures 3 and 4, it will be seen that a modified form of the invention is disclosed and in which a pair of arms 51 are pivotally connected together intermediate their ends as shown at 52. Each of the arms is provided with a semi-circular extension 53 which is provided at the free end thereof with a reduced portion

20 54. These reduced portions of the semi-circular extensions 53 overlap each other as shown in Figure 4. It will be appreciated that the semi-circular extension 53 may be elongated and conform to the shape of the
25 member 36 shown in Figure 2. The upper ends of the arms are likewise semi-circular to receive the pole or bar 15. The upper free ends of the arms are inbent and aline to form straight portions 54 which are adapt-
30 ed to receive a grooved roller 55. The portions 54 are inserted into the opposite ends of an axial passage 56 of the grooved pul-
ley 55.

10th 53. The lower extension 53 instead of being reduced as shown at 54 may be placed in juxtaposition, with the free ends of a sufficient length to prevent the ends from being readily displaced from the eyes 28 of the curtain 10.

40 curtain 10. In applying the rings shown in Figure 3, the arms 51 are moved away from each other until an upper end of one of the arms is removed from the axial passage 56 in the grooved pulley 55. The upper end of the arm is slipped over the pole 15 with the pulley 55 resting on said pole or rod. When the upper ends of the arms 51 are moved away from each other at this time the lower extensions 53 are likewise displaced with the overlapped portions 54 being moved away from each other so that the free ends of overlapped portions 54 may be readily inserted within an eye 28 of the curtain 10. When the upper ends of the arms are moved towards each other with the straight portions 54 being inserted within the passage 56 of the grooved pulley 55, the ends 54 of the extension are again returned to their operative overlapped position for receiving the eyes 28 and for supporting the curtain. The grooved roller will maintain the rings in a plane at right angles to the axis of the pole 15 at all times and provide for a ready manipulation of the curtain either to an operative or inoperative position.

What we claim is:

1. A ring for shower curtains comprising a pair of arms pivotally connected together at one of their adjacent ends, the opposite ends having straight portions movable into alignment with each other, said arms being curved to provide sufficient space to receive a rod, a tubular member having an axial passage adapted to receive the aligned straight portions and to aid in maintaining the straight portions in aligned positions. 70 75

2. A ring for shower curtains comprising a pair of arms pivotally connected together at one of their adjacent ends, the opposite ends having straight portions movable into alignment with each other, a tubular member having an axial passage adapted to receive the aligned straight portions of the arms.
